UNITED STATES PATENT OFFICE.

RAFAEL VACHIER, OF BATON ROUGE, LOUISIANA.

CARBONIZING AND REVIVIFYING RETORT.

Application filed December 17, 1923. Serial No. 681,251.

To all whom it may concern:

Be it known that I, RAFAEL VACHIER, a citizen of the United States, residing at Baton Rouge, parish of East Baton Rouge, 5 and State of Louisiana, have invented certain new and useful Improvements in Carbonizing and Revivifying Retorts, of which the following is a specification.

This invention relates to carbonizing and 10 reburning furnaces or kilns, and has for one of its objects to provide a kiln which is particularly adapted for the initial production or for the revivification of mineral and vegetable filtering and decolorizing carbons, 15 and similar materials, such for example as kieselghur, and the like.

A further object of the invention is to 20 provide an apparatus of the class described, in which the carbonizing or revivifying process may be carried on continuously.

A still further object of the invention is 25 to provide an apparatus of the class described in which the revivification of spent decolorizing carbons may be carried on, without the danger of breaking down such carbons and rendering them useless.

A still further object of the invention is 30 to provide an apparatus of the class described which will be simple in construction, comparatively inexpensive to manufacture and install and more efficient in operation than those which have been heretofore proposed.

With the above and other objects in view 35 which will appear as the description proceeds, the invention consists in the novel details of construction and combinations and arrangements of parts, more fully herein-after described and particularly pointed out 40 in the appended claims.

Referring to the accompanying drawings forming a part of this specification in which like reference characters designate like parts in all the views;

45 Figure 1 is a side elevational view, partly in section, of a furnace or kiln constructed in accordance with the present invention;

Fig. 2 is a fragmentary end elevational view of the parts shown in Fig. 1, as seen 50 from the left of the latter figure;

Fig. 3 is a fragmentary sectional plan view, taken approximately on the plane indicated by the line 3—3 of Fig. 1, looking down; and

55 Fig. 4 is a detail vertical sectional view

through the dust collector illustrated in Figs. 1 and 3.

In the said drawings the numeral 5 indicates a furnace or oven, preferably constructed of brick or other refractory material, provided with a combustion chamber 6, which may be divided by the horizontal baffle wall 7, substantially as shown in Fig. 1, and which furnace may be fired in any suitable manner, as for example, by means 60 of an industrial oil or fluid fuel burner, indicated diagrammatically at 8. The said furnace is provided with a suitable stack 9, communicating with the top thereof to lead off the products of combustion, and it is also 65 provided with an auxiliary flue or passage 10, controlled by a suitable damper 11, leading to an air heating chamber 12, associated with a predrying drum 13. A pipe 14 leads 70 from the air heating chamber 12 to the stack 75 9 to carry off the hot gases after they have performed their work in heating the air within the chamber 12, as will presently appear.

The predryer drum 13 preferably takes 80 the form of a metal cylinder, rotatably mounted upon suitable supports or rollers 14, and adapted to be driven by means of a pinion 15, engaging a gear 16, carried by the said drum, the said pinion being suitably 85 driven from any source of power, not shown.

The ends of the said cylinder or drum 13 extend respectively into the housings, 17 and 18, and may be provided with suitable gas-tight joints, not shown. The housing or receptacle 17 is provided with a suitable feed hopper 19, which communicates with a chute 20, whereby the carbon material may be introduced into the predrying drum 13, as will 90 likewise appear more fully below. The 95 housing 17 is further provided with a plurality of baffle plates or members, 21 and 22, which serve to break up the air currents travelling through the said housing, and to thereby cause the deposition of such carbon particles as may be carried back into the said housing by the said air currents. The 100

housing 17 is also provided with an exhaust pipe or passage 24, in which is mounted an exhaust fan 25, which may be driven 105 by means of a pulley 26, from any suitable source of power not shown.

The end of the drum 13, which enters the housing 17, constitutes the inlet end, while the end which enters the housing 18 consti- 110

2
tutes the discharge end, the said drum being preferably inclined slightly, as shown, so that when rotated the carbon material will be constantly fed from the higher end to 5 the lower end in the well known manner. The housing 18, which receives the discharge end of the drum, is provided with a discharge pipe or passage 28, which discharges the carbon material into a horizontally dis- 10 posed trough 30, in which is suitably jour- nalled a screw, ribbon or other conveyor 31, which conveyor may be driven by the pulley 32, see Fig. 2, from any suitable source of power not shown.

15 The trough 30 extends transversely of the apparatus, and is adapted to discharge through a plurality of outlet connections 32 into the longitudinally extending feed troughs 33, as will be clear from Figs. 1, 2 20 and 3, of the drawings. The said feed troughs 33 are each provided with a suitable conveyor 34, which may be driven in any suitable manner as, for example, by means of the bevelled gears 35 and 36 from a shaft 25 37, provided with the pulley 38, adapted to receive power from any suitable source not shown. It will be noted that the troughs 30 and 33 are covered so as to prevent the carbon particles from escaping therefrom and 30 becoming lost.

Each of the troughs 33 discharges into a plurality of vertically arranged retort tubes 40, which tubes extend downwardly through the top wall 41 of the furnace, the horizontal baffle 7 and the bottom wall 42, as 35 will be clear from Fig. 1. The said tubes may be, say from 4 to 10 inches in internal diameter, and 10 feet or more in length, and they are provided at their lower ends with 40 suitable discharge or sluice valves 44, whereby the discharge of the carbon material therefrom may be controlled, as by the rod member 45, extending outside the furnace walls.

45 The said tubes discharge into a trough 46, which may be partially filled with water, as shown in Fig. 1, to provide a water seal whereby air may be prevented from becoming entrained within the retort tubes to the 50 end that combustion of the carbon therein will be prevented. The said trough 46 dis- charges into a receptacle 47, which may be provided with a suitable agitator 48, and with an outlet pipe 49, through which the 55 carbon material may be withdrawn and transferred to its point of use in the well known manner.

The air heater 12 may be of any suitable construction, but is here shown as comprising a closed chamber or housing through which the hot gases from the combustion chamber may pass from the pipe 11, the said chamber being provided with a plurality of tubes or pipes 50, passing through the front and back walls thereof and through which

air may pass, being drawn therethrough by the suction fan 25.

As the air passes through the said tubes, it will of course be heated by the hot gases surrounding the tubes, and it will then be drawn through the housing 18 into the drum 13 and thence through the housing 17 to the discharge pipe 24. While in the drum 13, it will be brought into contact with the carbon material therein, and will serve to evaporate the moisture contained in the said material, and to thus predry the same.

This predrying is an important feature of the invention, since it has been found in actual practice that when the moist carbon material is introduced directly into retort tubes, which are substantially red hot, the steam which is liberated tends to break down the structure of the carbon and render it unfit for further filtering and decolorizing use. Furthermore, the friction of the wet material passing through the various parts of the apparatus is very great and this is substantially eliminated by first drying the material in the manner above indicated.

90 The operation of the apparatus will be clear from the foregoing, but it will be briefly summarized as follows.

Carbon material, whether it be material from which decolorizing carbon is to be 95 initially prepared or whether it be decolorizing carbon which has already been used and which it is desired to revivify, is placed in the hopper 19, from which it is fed through the chute 20 into the upper end of the drum 13. This said drum being rotated by means of the pinion 15 and gear 16, carbon will travel along its interior surface to the discharge end thereof, while being subjected to the drying action of the heated air sucked through the said drum by the exhaust fan 25. Any carbon particles which may be 100 drawn back into the housing 17 will be effectively stopped by the baffles 21 and 22, and will be deposited in the lower portion 105 of the said housing 17, from which they may be withdrawn at will through the opening of the valve 55 with which the said housing is provided.

110 The dried carbon will be discharged at the lower end of the drum 13 into the housing 18, from whence it will pass through the discharge pipe 28 into the transverse trough 30. The conveyor 31 in the said trough will move the said carbon along the interior 115 thereof and discharge it into the various longitudinally extending troughs 33, where it will in turn be moved by means of conveyors 34 to the various openings leading to the retort tubes 40. It will pass down 120 through these latter tubes and the valves 44 being closed, will completely fill the latter so as to exclude all air therefrom, whereupon it will be subjected to the usual revivifying or burning temperature of between 1400 and 130

1600 degrees F. After the apparatus is once started, the valves 44 may be manipulated in such a manner as to permit of a substantially continuous flow of the carbon through the various parts of the apparatus, always maintaining the retort tubes 40 full of carbon so that the air may be excluded therefrom.

The burned or revivified material is discharged from the lower ends of the tubes 40 into the trough 46, from which it is carried by the water flowing therein into the mixing tank 47, from whence it may be pumped to the point where it is to be used.

It will further be noted that the flow of carbon through the retort tubes, while in its heated condition, is due solely to the action of gravity which has a tendency to prevent any grinding action which might result from the employment of mechanical means for moving the carbon through said tubes, with the resultant impairment of the physical structure of the carbon, whereby it might be rendered useless for further filtering and decolorizing purposes.

In order to further dry the carbon before it is introduced into the retort tubes, if desired, a manifold or header 56 may be connected by means of pipes 57 to each of the troughs 33, and it may be in communication through a pipe 58 with the stack 9, whereby a certain amount of air circulation within the feeding troughs 33 will be set up. In order to prevent the escape of carbon particles through this portion of the apparatus when it is employed, a separating chamber or catch-all 60 may be interposed in the pipe 58, which chamber, as is best shown in Fig. 4, is provided with the baffles 61 and 62 and with the water spray pipes 63 and 64, whereby any particles of carbon which may enter the said chamber may be separated from the air and deposited therein. They may be withdrawn from the said chamber by the discharge pipe or passage 65, as will be readily understood.

While one form of the invention has been illustrated and described, it is obvious that those skilled in the art may vary the details of construction as well as the arrangement of parts, without departing from the spirit of the invention, and therefore it is not wished to be limited to the above disclosure except as may be required by the accompanying claims.

What is claimed is:

1. In an apparatus of the class described, a combustion chamber; a plurality of retort tubes in said combustion chamber; a predrying chamber comprising an inclined rotatable drum; means for feeding carbon material into said predrying chamber; means for producing a flow of air through
2. In an apparatus of the class described, a combustion chamber; a plurality of retort tubes in said combustion chamber; a predrying chamber comprising an inclined rotatable drum; means for feeding carbon material into said predrying chamber; means for producing a flow of air through
3. In an apparatus for producing and revivifying filtering and decolorizing carbons, a combustion chamber provided with a stack; a plurality of rows of substantially vertical retort tubes passing through said combustion chamber through which carbon material may pass by gravity; closed troughs connected to the inlet ends of the tubes in each row; conveyer means in said troughs for feeding carbon material therethrough to said tubes; connections between said stack and said troughs for creating a circulation of air in the latter; and a liquid seal associated with the discharge ends of said tubes.
4. In an apparatus for producing and revivifying filtering and decolorizing carbons, a combustion chamber provided with a stack; a plurality of rows of substantially vertical retort tubes passing through said combustion chamber through which carbon material may pass by gravity; closed troughs connected to the inlet ends of the tubes in each row; conveyer means in said troughs for feeding carbon material therethrough to said tubes; connections between said stack and said troughs for creating a circulation of air in the latter; a trap chamber in said connections for preventing carbon particles from being drawn into said stack; and a liquid seal associated with the discharge ends of said tubes.
5. In an apparatus for producing and revivifying filtering and decolorizing carbons, a combustion chamber; a plurality of substantially vertical retort tubes arranged in rows, passing through said combustion chamber; a plurality of conveyers for feeding carbon material to the upper ends of said tubes; a predrying chamber; and an additional conveyer arranged to receive carbon material from said predrying chamber and to distribute it to said first named conveyers.

said predrying chamber; means for heating said air; and means for feeding the carbon material from said predrying chamber to said retort tubes.

2. In an apparatus of the class described, a combustion chamber; a plurality of retort tubes in said combustion chamber; a predrying chamber comprising an inclined rotatable drum; means for feeding carbon material into said predrying chamber; means for producing a flow of air through said predrying chamber; means adjacent one end of said drum for heating said air; means for leading a portion of the products of combustion from said combustion chamber to said air heating means; and means for feeding the carbon material from said predrying chamber to said retort tubes.

3. In an apparatus for producing and revivifying filtering and decolorizing carbons, a combustion chamber provided with a stack; a plurality of rows of substantially vertical retort tubes passing through said combustion chamber through which carbon material may pass by gravity; closed troughs connected to the inlet ends of the tubes in each row; conveyer means in said troughs for feeding carbon material therethrough to said tubes; connections between said stack and said troughs for creating a circulation of air in the latter; and a liquid seal associated with the discharge ends of said tubes.

4. In an apparatus for producing and revivifying filtering and decolorizing carbons, a combustion chamber provided with a stack; a plurality of rows of substantially vertical retort tubes passing through said combustion chamber through which carbon material may pass by gravity; closed troughs connected to the inlet ends of the tubes in each row; conveyer means in said troughs for feeding carbon material therethrough to said tubes; connections between said stack and said troughs for creating a circulation of air in the latter; a trap chamber in said connections for preventing carbon particles from being drawn into said stack; and a liquid seal associated with the discharge ends of said tubes.

5. In an apparatus for producing and revivifying filtering and decolorizing carbons, a combustion chamber; a plurality of substantially vertical retort tubes arranged in rows, passing through said combustion chamber; a plurality of conveyers for feeding carbon material to the upper ends of said tubes; a predrying chamber; and an additional conveyer arranged to receive carbon material from said predrying chamber and to distribute it to said first named conveyers.

RAFAEL VACHIER.
